COMBINATION ASH RECEIVER AND
EXTINGUISHERLee R. Akers and James C. Wilkinson,
Kansas City, Mo.

Application April 26, 1939, Serial No. 270,144

8 Claims. (Cl. 131—237)

This invention relates to a combination ash receiver and extinguisher for cigars and cigarettes, the principal object of the invention being to provide a device of this character which positively snuffs out the fire in a discarded cigar or cigarette and thereby avoids the obnoxious odors of smoldering tobacco.

We are aware that various mechanisms have been devised for crushing the lighted end of a cigar or cigarette as it is being placed in a receiver. The crushing action, however, spreads the hot ashes and they drop into the receiver and set fire to the contents. Another defect of such devices is that the snuffing pressure may not be applied for a sufficient time to extinguish the fire and even with devices which retainingly engage the discarded butt the immediate insertion of a subsequent cigar or cigarette releases the engagement before the fire is completely extinguished with the result that the fire continues after the discarded butt has dropped into the receiver.

It is, therefore, a further object of the invention to provide a combination ash receiver and extinguisher which includes a magazine type of gripping mechanism that successively advances the engaged cigarettes toward a releasing position thereby allowing sufficient time for the fire to become extinguished.

Further objects of the invention are to provide a device of this character which is of simple and inexpensive construction, and to provide a gripping mechanism which extinguishes the fire without sufficient crushing to cause ashes to drop into the container.

In accomplishing these and other objects of the invention, as hereinafter pointed out, we have provided improved details of structure, the preferred form of which is illustrated in the accompanying drawings, wherein:

Fig. 1 is a perspective view of a combination ash receiver and fire extinguisher constructed in accordance with the present invention.

Fig. 2 is a similar perspective view showing the housing removed to better illustrate the gripping or snuffing magazine.

Fig. 3 is a cross-section through the device on the line 3—3 of Fig. 1.

Fig. 4 is a section through the device on the line 4—4 of Fig. 3.

Fig. 5 is a similar section on the line 5—5 of Fig. 3.

Fig. 6 is a detail perspective view of one of the flexible disks forming a part of the gripping magazine.

Fig. 7 is a detail perspective view of one of the side plates supporting the gripping magazine.

Referring more in detail to the drawings:

1 designates a combination ash receiver and extinguisher constructed in accordance with the present invention, and which includes a base 2 having a shouldered perimetrical edge 3 to telescopically receive the side walls 4 of a hood-like housing 5. The top 6 of the housing is provided with a depression 7 forming a tray in which cigarettes or cigars are placed in the manner of a conventional tray.

Also formed in the top 6 is a slotted opening 8 through which burning cigar or cigarette butts are placed in the fire extinguishing mechanism 15 later described. The opening 8 is preferably partly covered by a hood-like guard 9 forming a passageway 10 for the projecting ends of the cigarette butts as they are advanced in the extinguishing mechanism. The housing 5 thus cooperates with the base to form a closed receptacle for discarded cigars and cigarettes and to enclose the extinguishing mechanism now to be described.

The extinguishing mechanism is best illustrated in Fig. 2 and includes a frame 11 comprising spaced side plates 12 and 13. The plates 12 and 13 are of the same construction in that each includes a leg portion 14 having a laterally extending foot flange 15 secured to the side edges 25 of the base by fastening devices 16. The body portion 17 of the plate is offset inwardly, as at 18, to support the gripping or carrier magazine 19. When the plates are in position on the base the body portions 17 thereof are spaced apart 30 an ample distance to allow the passage of a cigar butt therebetween as best shown in Fig. 3.

Located in the body portions of the side plates, at points directly below the uncovered portion of the opening 8, are bearing openings 20 journailling a rotatable shaft 21 of the magazine 19. The shaft 21 has an enlarged portion 22 forming shoulders 23 and 24. Mounted on the shaft and engaging the shoulders 23 and 24 are flexible circular disks 25 and 26 that are normally spaced apart slightly less than the diameter of a cigarette. The disks are clamped against the shoulders by nuts 28 and 29 threaded on the shaft so that they rotate as a single unit when the shaft is actuated, as later described. As just stated, the disks are flexible and are formed of spring-like, incombustible material whereby they exert a clamping influence on a cigarette placed therebetween and are adapted to be spread apart at selective points in their rotation to respectively 45 50 55

receive and release a cigarette or cigar butt as later described.

In order to control flexure of the disks, the body portions 17 of the side plates are provided with upwardly extending arms 30 terminating at the upper edges of the disks in downwardly turned fingers 31 which extend over the rims of the disks and engage the inner faces thereof, as clearly shown in Fig. 2. Since the side plates have greater spacing than the spacing of the disks on the shaft, the upper portion of the disks registering with the opening 8 are spread apart sufficiently to permit the cigar or cigarette butt to drop readily therebetween.

Also formed as a part of the side plates at points spaced below a plane extending through the horizontal axis of the shaft are inturned fingers 32 which also engage the inner faces of the disks to spread them apart and thereby form a place of release for the engaged cigarette butts.

Carried by one of the side plates, just below the fingers 32, is an inclined ejector tongue 33 extending between the disks to engage the cigarettes as the magazine is rotated and effect positive discharge thereof from the magazine. The tongue 33 is spaced a sufficient distance from the opening 8 to allow the cigarettes or cigar butts to be retained in the magazine until the fire has become extinguished even though burning butts are placed in the magazine in rapid succession.

The magazine shaft 21 projects a sufficient distance through one of the side plates to carry a ratchet wheel 34 having laterally directed teeth 35 provided with shoulders 36 that form abutments to be engaged by a pawl 37. The ratchet wheel is of disk-like character and is mounted upon a reduced extension 38 of the shaft. The reduced extension thus forms a stop shoulder 40 against which the ratchet is rigidly clamped by a nut 39 threaded on the shaft extension. The pawl 37 is preferably mounted on the shaft extension and has an offset arm portion 40 extending toward the body portion of the ratchet wheel 45 to engage the ratchet teeth. The arm is retained in yielding engagement with the ratchet wheel by means of a coil spring 41 sleeved over the shaft and bearing against the outer face of the pawl. The opposite end of the spring engages 50 against a nut 42 that is threaded on the shaft extension to load the spring sufficiently so that the arm portion of the pawl is at all times retained in contact with the ratchet wheel.

Formed on the outer end of the arm 40 is a head 43 having pin and slot connection 44 and 45 with a reciprocating lever 46. The lever 46 is reciprocably mounted in a slot 47 that is formed in the top 6 alongside the guard 9. The upper projecting end of the lever is shaped to 60 form a thumb plate 51 against which pressure is applied to effect reciprocation of the actuating lever. The opposite end of the lever has a reduced extension 52 slidably mounted in a tubular guide 53 that is supported on the base 2 directly 65 below the slot 6. In order to retain the actuating lever in its uppermost position the shaft 21 carries a coil spring 54 having one end terminating in an arm 55 anchored to the adjacent side plate by a tongue 56. The opposite end 70 of the coil spring terminates in a similar arm 57 that is anchored to a similar tongue on the head 43 of the pawl. It is thus obvious that the spring exerts pressure to retain the actuating lever in its uppermost position.

By observing Fig. 3 it will be noted that due

to the location of the fingers 31 and 32, that portion of the disks extending between the respective fingers is drawn closely together as indicated at 58 and that this spacing narrows from a maximum width directly adjacent the arms 31 to a minimum width at a point midway between the ears 31 and 32 where the spacing again increases to the maximum adjacent the ears 32 as indicated at 59. Therefore when a lighted cigarette is dropped through the opening 8 it falls 10 freely between the spread portion of the disks but is stopped when the lighted end engages the disks so that it extends radially therefrom as shown in dotted lines *a* in Fig. 5. Then when the lever 46 is depressed so that the pawl engaging one of the ratchet teeth advances the disks one space, the cigarette is moved in an anti-clockwise direction (Fig. 5) as indicated by the dotted lines *b*. Since the disks are gradually drawn toward each other, the burnt end of the cigarette is caused to be gripped sufficiently tight to snuff out the fire, however, the gripping action does not crush the cigarette with sufficient force to cause dropping of burned particles into the container. The gripped cigarette thus remains in engagement with the disks so that the pressure has sufficient time to snuff out the fire. When another cigarette is dropped through the opening 8 and the lever pressed, that cigarette is carried by the disk into gripping contact and 30 the previous cigarette is advanced further into the container toward the point of release. After a number of cigarettes have been inserted, the first cigarette reaches engagement with the tongue 34. At this point pressure on the disks 35 is relieved and the tongue forcibly releases the cigarette should it tend to adhere to the faces of the disks.

It is obvious that even though the lever be operated a sufficient number of times to move 40 an inserted cigarette to the point where it is released, it has been retained in gripping engagement by the disks sufficient time to allow complete extinguishment of the fire. The same is true if a number of burning cigarettes have 45 been rapidly placed in successive order in the machine.

From the foregoing it is obvious that we have provided a combination ash receiver and extinguisher which is of simple construction and 50 which is adapted to apply the required snuffing pressure until the fire has time to become extinguished.

What we claim and desire to secure by Letters Patent is:

1. In a device of the character described a carrier including a pair of axially aligned yieldable members for grippingly retaining the burnt end of a cigarette therebetween and under pressure, means for ejecting the cigarette, and means 60 for advancing the carrier to bring the cigarette to said ejecting means.

2. A device of the character described including a housing having an opening for the insertion of cigarettes, a pair of axially aligned members rotatable in the housing for grippingly engaging burnt ends of the cigarettes therebetween, and means for successively advancing said members to carry the cigarettes to a selected position in the housing.

3. A device of the character described including a housing having an opening through which cigarettes are inserted, a pair of flexible disks, a shaft supporting the disks at the sides of the opening, means for maintaining a fixed spacing 75

of the disk centers on the shaft to form gripping portions at the peripheries of the disks, means for spreading portions of the disks at selected points to facilitate insertion of and removal of the burnt end of cigarettes between the gripping portions of the disks, and means for effecting intermittent rotation of the disks.

5. A device of the character described including a housing having an opening through which cigarettes are inserted, a pair of flexible disks, a shaft supporting the disks at the sides of the opening, means for maintaining a fixed spacing of the disk centers on the shaft to form gripping portions at the peripheries of the disks, means 10 for spreading portions of the disks at selected points to facilitate insertion of and removal of the burnt end of cigarettes between the gripping portions of the disks, means for effecting intermittent rotation of the disks, and means for 15 ejecting the cigarettes.

6. A device of the character described including a housing having an opening through which cigarettes are inserted, a pair of flexible disks, means rotatably supporting the disks at the 20 respective sides of the opening, means for causing the disks to grip the burnt ends of the cigarettes during the major portion of each revolution of the disks, and means for effecting intermittent movement of the disks.

30 7. A device of the character described includ-

ing a housing having an opening through which cigarettes are inserted, a pair of flexible disks, means rotatably supporting the disks at the respective sides of the opening, means for causing the disks to grip the burnt ends of the cigarettes 5 during the major portion of each revolution of the disks, means for effecting intermittent movement of the disks, and means for successively ejecting the cigarettes from the disks.

8. A device of the character described including a pair of yieldable disks, means rotatably supporting the disks in spaced relation to grip the burnt end of a cigarette therebetween during the major portion of each revolution of the disks, means for rotating said disks, and means located 15 at a selective point with respect to the rotation of the disks for spreading the peripheries of the disks to release the gripped cigarette.

9. A device of the character described including a pair of yieldable disks, means rotatably 20 supporting the disks in spaced relation to grip the burnt end of a cigarette therebetween during the major portion of each revolution of the disks, means for rotating said disks, and spaced means 25 spreading the disks at selective points for admitting a cigarette to be gripped and for releasing the gripped cigarette.
